BROADCASTING ANTENNA SYSTEM

Andrew Alford, New York, N. Y., assignor to International Telephone & Radio Manufacturing Corporation, a corporation of Delaware

Application September 25, 1940, Serial No. 358,214

13 Claims. (Cl. 250—11)

This invention relates to antenna systems and more particularly antenna units and arrays for broadcasting energy at high frequencies.

In high frequency broadcasting systems such as are used for television and frequency modulation transmission certain new problems arise. Since the high frequencies used have generally only a line of sight coverage it is desirable that the broadcasting antenna be mounted as high above the earth as possible. It is also desirable that the radiation pattern from the antenna be directed in a horizontal direction in order that the signal level be high at points distant from the transmitter. In order to obtain this concentration of energy it is necessary to provide an array of antenna units or other means for concentrating the energy. Since the antenna is to be supported at a high point and consists of an array of units, it is essential for practical reasons that the units be relatively small and produce a high radiation characteristic so that a good signal strength may be obtained without a huge structure or extensive array mounted high above the ground.

Furthermore, since the antenna is usually mounted in a relatively inaccessible place, such as a mast on the top of a high building, it is desirable that the units be made so as to require a minimum of maintenance.

The broadcasting stations particularly for television and frequency modulation, are generally located in areas of dense population in order to reach the maximum number of people in the relatively limited coverage area. Accordingly, the antenna units may be located above the heads of passers-by and the hazards accompanying the accumulation of ice on the units would be quite high. Ice accumulated during a sleet storm may fall and cause considerable damage to people passing by as well as to inanimate objects. Furthermore, such ice accumulations may fall from one unit to another unit of the antenna causing damage to parts thereof such as insulators.

Another consideration in broadcast antennae is the factor of insulation. Usually power in such broadcasting systems is relatively high and accordingly any insulators used in the antenna may be called upon to withstand considerable voltage stress.

It is an object of my invention to provide a broadcast antenna system for use at high frequencies in which the antenna units are small in dimensions and produce relatively great power output.

It is a further object of my invention to provide an antenna unit which may be supported on a metal mast or support without the necessity of any insulation therefrom.

It is a further object of my invention to provide a broadcast antenna system which may be readily mounted in a relatively inaccessible place, will be relatively small for a given concentration of energy and will need a minimum of attention.

It is a still further object of my invention to provide a broadcast antenna system which operates to produce substantially pure horizontally polarized waves.

A better understanding of my invention, as well as the objects and features thereof, may be had from the following description taken with reference to the accompanying drawings, in which

Fig. 1 illustrates a broadcast array in accordance with my invention;

Fig. 2 shows curves illustrating characteristics of an array in accordance with my invention;

Fig. 3 is a diagrammatic illustration of a preferred form of antenna unit in accordance with my invention;

Figs. 4 and 5 illustrate a preferred structural arrangement of an antenna in accordance with my invention;

Fig. 6 illustrates a detail of the energizing lines used for energizing antenna in accordance with my invention;

Fig. 7 illustrates a plurality of units of the type shown in Figs. 4 and 5 mounted as an array;

Fig. 8 illustrates a heating system which may be used in an antenna in accordance with my invention;

Figs. 9 and 10 show alternative structural features for an antenna of the type shown in Figs. 3, 4 and 5, and

Figs. 11 and 12 show alternative forms of antenna units.

In Fig. 1, 10 represents a supporting mast or structure upon which are mounted antenna units 11, 12, 13. These antenna units are such that the radiation pattern from each unit produces a toroidal pattern with its minimum at the center of the unit and having substantially circular radiation in the horizontal plane. Suitable antenna units for producing such radiation pattern are disclosed more fully in my previous application, Serial No. 270,173 filed April 26, 1939.

It is known to produce a horizontal concentration of energy by arranging antenna units in a vertical array. However, if crossed dipoles are

used it is evident that two units must be pro-

vided at each point in order to secure substantially uniform coverage. Thus, considering for example, two uniform radiating units spaced a distance s , such as 11 and 12 of Fig. 1, if a pair of crossed horizontal dipoles are used for each unit then only half of the energy fed to the two units is applied to those dipoles in the plane of the paper, the other two dipoles at right angles with those in the plane of the paper receiving the other half of the energy. On the other hand with antenna units having a toroidal distribution and a characteristic pattern of uniform distribution in the horizontal plane, it is evident that energy will be equally radiated in all directions upon energization of the unit. Accordingly, two such units furnished with a given power will produce substantially the same radiation in a horizontal field as will four dipoles arranged as described above supplied with nearly twice the power.

With a plurality of antenna units, such as 11, 12 and 13 of Fig. 1, arranged in a vertical array with a separation s as shown therein, it is evident that a certain degree of concentration of energy in the horizontal may be achieved. When such units are arranged in an array, optimum concentration may be obtained by proper spacing of the units. With an antenna producing the substantially toroidal radiation pattern as described above, the power gain in the horizontal direction for any number n unit, may be expressed by the following equation:

$$P = \frac{1}{3} \frac{n^2}{1 + 2(n-1)\phi(s) + 2(n-2)\phi(2s) + \dots + 2'\phi[(n-1)s]}$$

where

$$\phi(s) = -\frac{\cos s}{s^2} + \frac{\sin s}{s^3}$$

$$\phi(2s) = -\frac{\cos(2s)}{(2s)^2} + \frac{\sin(2s)}{(2s)^3}$$

$$\phi(n-1)s = -\frac{\cos(n-1)}{(n-1)^2} + \frac{\sin(n-1)}{(n-1)^3}$$

n =number of antenna units in array.

s =spacing expressed in radians

$$\frac{2\pi}{\lambda} \text{ (spacing in meters).}$$

λ =wavelength in meters.

Curves for satisfying the equation given above are plotted for $n=2$ and $n=4$ in Fig. 2. From these curves the desired spacing between adjacent units may be readily obtained for any desired power gain. It is preferable, in any case, when a desired gain is to be provided, that the ascending portions of the curves up to the substantial maximum thereof should be used. Thus, in curve 1 it is seen that the maximum occurs between 320 and 340 degrees. Consequently, if a power gain of 2 is desired, two units may be used and the units may be spaced between 260 and 340 degrees, one from another. For this particular set-up it is clear that the power gain decreases very slowly for spacings above 320 degrees and a spacing up to 400 degrees is entirely feasible. However, because of space limitations the narrower spacing is usually desirable, and for this reason the curve need not be used beyond the maximum point.

If, on the other hand, a greater power gain is desired, a four-unit array may be used having

the characteristic of curve #2 of Fig. 2. It can be seen that such an arrangement will give a power gain of substantially 4.6 at the maximum. For any other desired number of units, spacing curves such as shown in Fig. 2 may be readily plotted from the equation and a suitable spacing chosen to secure the desired power gain.

Curves 1 and 2 of Fig. 2 are drawn for an arrangement wherein equal power is supplied to the various antennae. Such an arrangement will produce maximum gain in a horizontal direction for the desired number of units. It is known, however, that with such an array wherein equal power is fed to each of the units, a number of minor lobes will be produced. Generally, these minor lobes will not be bothersome since the angle of null between the first minor lobe and the ground will usually be such that the null point at the earth's surface will be quite close to the transmitting antenna. Furthermore, in built up areas sufficient reflection from adjacent buildings will ordinarily occur so that no null will be observed. However, if the null point and the minor lobes are found to be objectionable they may be obviated by a suitable division of power in the antenna unit. This contemplates energization of the center unit at a higher degree than the outer units in a manner known in the art. If it is not desired to entirely eliminate the minor lobes but merely avoid the null so that there will be some radiation in the minimum direction between lobes, a small degree of

inequality of energization between the units may be utilized.

In Fig. 3 is shown a new type of antenna unit in accordance with my invention particularly suitable for vertical broadcast arrays of the type shown in Fig. 1. This antenna comprises four radiating members 30, 31, 32, 33 arranged in the form of a square or other closed pattern. Energy from high frequency source 34 is fed over a line 35 and branch conductors 36, 37 to radiating members 30, 31. Lines 36, 37 are arranged so as to energize the members 30, 31, adjacent their mid-points in phase opposition. Accordingly, members 30 and 31 will operate to excite in the arms 32, 33 energy such that these members will be oppositely poled at their ends. Members 32 and 33 are preferably turned inwardly as indicated at 38 in order to increase the capacitive coupling of the system. It will be evident from the description given that each of the arms 30, 31, 32 and 33 will have substantially a voltage node at its mid-point. Accordingly, the members may be supported directly at their centers and need not be insulated at these points with respect to one another or to the ground. This antenna unit will produce substantially pure horizontally polarized energy thus avoiding re-radiation or absorption of the energy by vertical objects in the field. Accordingly, guy wires for the support will not interfere with the broadcast in any way. Furthermore, since the units are small in size and light in weight they may be mounted on a mast or support above the guy wires supporting a tower or the like.

A practical constructional form of antenna similar to Fig. 3 is illustrated in Figs. 4, 5 and 6. In Fig. 4, antenna members 30, 31, 32, 33 are shown as formed of hollow tubing. At the center of each of these elements are provided other

supporting tubes 49, 41, 42, 43 which may be of metal and may be connected at one end firmly by brazing or welding to the antenna element, and at the other end may be firmly fixed mechanically to a metallic supporting mast or pole 44. Since the antenna members 30 to 33, inclusive, are each supported at voltage nodal points, it is unnecessary to provide any insulation for the radiating elements. The members 30, 31 may be energized by shielded leads contained inside the mast 44 and the tubular cross arms 40, 41 as indicated at 50, 51 of Fig. 5. The ends of the conductors inside the shielded lines may be spread apart as shown at 51', 52 so as to secure the desired impedance match.

A better understanding of the detail of a cable suitable for use may be had by reference to Fig. 6. In this arrangement leads 51 are shown inside a metallic outer sheath 60. The conductors 51 may be brought out through an insulator 61. The ends 52 thereof may be then spread apart for connection to the bar antenna conductor 31. It can be seen that with such an arrangement the entire power supply wiring system and all of the insulators thereof are housed within the tubular metallic portions of the antenna and are thus protected from the weather and any mechanical stress.

The antenna units of the type shown in Figs. 4 and 5 may be readily formed in an array in a manner disclosed in Fig. 7. In this arrangement four radiator units are shown 10, 11, 12 and 13 mounted on a common transmitter mast 14. A shielded conductor feed line 15, is connected to a branch transmission line 16, 17, the ends of which are connected to further branch lines 18, 19 which serve to supply energy respectively to antenna units 12, 13 and 10, 11. In order to match the impedance of the transmission line at the various junction points building-out elements may be bridged across as indicated at 80. It is clear that the antenna array provided in Fig. 7 is of such a nature that the antenna elements may be readily installed in any desired tower since insulation between the various units and the mast, as well as between one another on the support, need not be provided. Furthermore, all of the insulation and wiring of the units may be contained wholly within the antenna structure itself, as shown in Fig. 5 and therefore the system is not subject to mechanical damage by objects falling on the unit for example.

The size of the loop used in the system, in accordance with my invention, is relatively small. For example, if it is desired to operate the system at 46 megacycles, the antenna unit may be made to have an outside dimension of substantially three feet. The antennae themselves may be made of relatively rigid material such as aluminum channel about 3 or 4 inches wide and from 3 to 4 inches deep. It is, therefore, evident that the unit may be rigidly fixed on a mast in a self-supporting fashion without danger of wind causing any substantial variation in the relative position of the parts of the antenna.

A further advantage of antenna units constructed in the manner shown in Figs. 4 to 7, resides in the fact that heating elements for removing sleet formations may be readily applied without in any way affecting the operation of the system for radio frequency. This may be accomplished easily, in the manner indicated in Fig. 8, which shows a fragmentary section of an antenna showing only two members such as 30, 33. In each of these members may be pro-

vided resistance elements 81, 82 which may be connected directly to the grounded antenna members at the opposite ends and which may be connected to a supply of heating current, at their mid-points by conductors 83, 84 respectively, by way of a switch such as 85, if desired.

Antennae of the type shown in Figs. 3 to 8, inclusive, may be made in other forms, if desired. For example, in Fig. 9 the circular antenna form is shown comprising four antenna arms 90, 91, 92, 93 provided with supporting elements 94, 95, 96, 97, so that they may be supported from a hollow post or mast 98. The ends of the radiating members are shown tuned in at 99 to provide the desired capacitive coupling therebetween.

In Fig. 10 still another form which the antenna, in accordance with my invention, may take, is shown. In this arrangement each of the arms 30, 31, 32, 33 is shown bent at right angles at the center point, the arms 32, 33 being provided with overlapping portions 36 which serve to produce the desired capacitive coupling. Supporting arms 40, 41, 42, 43 connected to a supporting mast 44, are shown. It is clear in this connection that the energizing leads extending from arms 40 and 41 to elements 30, 31 may be brought out so as to contact the radiator at substantially 90°.

Accordingly, adjustment of the spacing between lead 51 or lead 52 may be carried out without any substantial change in the length of these conductors. This design presents an advantage over that illustrated in Figs. 4 and 5 in that the adjustment of spacing between conductors 51' or conductors 52 does not necessitate so great a change in length and may be carried out without having to actually cut the conductor to the desired length.

The examples so far considered have been directed to antenna units comprised of four members. However, the structure according to my invention is not limited to such a number of members. In fact any plural number of elements may be used to produce useful results so long as the members are maintained at a length under a quarter of a wavelength and have their adjacent ends interconnected by a relatively large reactance. It is clear, however, that when an odd number of members is used, the vertically polarized components of the wave will not be eliminated in every direction about the antenna.

In Fig. 11 is shown one form of antenna unit comprised of six members 111 to 116, inclusive. Energy is fed from a source 117 to each of members 111, 113 and 115 in such phase relation that the adjacent ends of the feed members are at opposite instantaneous potentials. Members 112, 114 and 116 are thus parasitically energized so as to produce at their midpoints voltage nodes. The required capacitive reactance between the adjacent members may be obtained, as shown, by turning in the ends of members 112, 114 and 116.

It is evident that since the members of Fig. 11 all have voltage nodes at their midpoints these members may be supported directly on a metal supporting pole or mast as in the systems of Figs. 3-8.

In Fig. 12 is shown an antenna unit made of three members, 121, 122 and 123. Members 121, 122 are directly fed from source 124 with energy such that their adjacent ends are at opposite instantaneous polarity and member 123 is parasitically energized therefrom so as to have a voltage node at its midpoint. The members are

made short with respect to a half wavelength, as in the other embodiments, and may be supported at their midpoints without requiring further insulation. However, the unit does not have the symmetry possessed by units made of an even plurality of members and consequently will not produce a uniform radiation in all directions. This departure, however, may be relatively small and may in some cases be desired.

While I have described my invention in connection with the accompanying drawings, it should be distinctly understood that these specific embodiments thereof are incorporated to facilitate the understanding of the invention merely by way of example, and are not to be construed as limitations on my invention. What I consider to be my invention and upon which I desire to secure protection is embodied in the accompanying claims.

What I claim is:

1. A broadcast antenna array comprising at least two antenna units, each unit having a transmitting characteristic for producing a pattern of substantially toroidal form having substantially uniform value in a horizontal plane, said units each being spaced apart vertically from the next adjacent unit a distance in the order of 200 to 400 electrical degrees at the operating frequency.

2. A broadcast antenna array according to claim 1, wherein said array comprises n number of units, the spacing between units being determined for a desired power gain P by the equation

$$P = \frac{1}{3} \frac{n^2}{1/3n + 2(n-1)\phi(s) + 2(n-2)\phi(2s) + \dots + 2\phi((n-1)s)}$$

where

$$\phi(s) = -\frac{\cos s}{s^2} + \frac{\sin s}{s^3}$$

$$\phi(2s) = -\frac{\cos 2s}{(2s)^2} + \frac{\sin 2s}{(2s)^3}$$

$$\phi(n-1) = -\frac{\cos (n-1)}{\cos (n-1)^2} + \frac{\sin [2(n-1)s]}{[(n-1)s^3]}$$

and s equals the spacing between units expressed in radians.

3. A broadcast antenna array according to claim 1, wherein said units each comprise metallic elements, metallic supporting means fastened substantially at the center of each of said elements, further comprising means for energizing certain of said elements at the operating frequency, a metallic tower and means for fastening said metallic supporting means directly to said tower.

4. A broadcast antenna according to claim 1, wherein at least three antenna units are provided, further comprising means for energizing respective ones of said units with predetermined different amounts of power.

5. An antenna unit comprising a plurality of members each member being of the order of one-tenth of a half wave-length at the operating frequency, capacitive reactance members interconnecting the adjacent ends of said members, and

means for feeding energy to at least two of said members adjacent their voltage nodal points in such phase relation that the adjacent ends of adjacent ones of said energy fed members are at potentials of opposed polarity, at least one of said members being parasitically energized by said energy fed members.

6. An antenna unit comprising an even plurality of members each member being short with respect to a half wave-length at the operating frequency, means for supplying energy to alternate ones of said members adjacent their mid-point to produce voltage nodal points thereat, in such phase relation that adjacent ends of adjacent ones of said energy supplied members are at opposed potentials, and capacitive reactance members interconnecting adjacent ends of said members.

7. An antenna unit comprising four members arranged in the form of a substantially closed pattern each of said members being short with respect to half a wavelength of the operating frequency, means for energizing oppositely positioned ones of said members at substantially their mid-points in opposite phase relationship, and means for capacitively coupling the other two members, respectively, between the opposite ends of said two members first mentioned.

8. An antenna unit according to claim 7, further comprising metal supporting arms fixed substantially to the mid-points of each of said members.

9. An antenna unit according to claim 7, fur-

ther comprising metal supporting arms fixed substantially at the midpoint of each of said members, and a metal supporting tower to which said members are fastened.

10. An antenna unit according to claim 7, further comprising a metal antenna supporting means, and means connected substantially at the midpoints of each of said members for mounting said unit on said supporting means.

11. An antenna unit according to claim 7 wherein said four members are each made of hollow metallic material, further comprising heating means in said hollow, and connections for energizing said heating means.

12. An antenna structure comprising an even plurality of radiant acting members each member being short with respect to a half wavelength at the operating frequency, said members being hollow in form, capacitive reactive means interconnecting adjacent ends of said members to provide in effect a loop, hollow metal supports fastened to each of said members at substantially the center thereof, and a metallic antenna mast, said supports being fastened to said metallic mast.

13. An antenna structure according to claim 12, further comprising energy supply lines arranged substantially within said supports, and means of connecting said supply lines to alternate ones of said members adjacent their mid-points to produce voltage nodal points thereat.

ANDREW ALFORD.
